US00D555605S

(12) **United States Design Patent** (10) **Patent No.:** **US D555,605 S**
Parnell (45) **Date of Patent:** **** Nov. 20, 2007**

(54) **REMOTE CONTROL ELECTRICAL SWITCH**

(76) Inventor: **Richard Erle Parnell**, 1989 Higby Dr.,
Stow, OH (US) 44224

(**) Term: **14 Years**

(21) Appl. No.: **29/257,300**

(22) Filed: **Mar. 31, 2006**

(51) **LOC (8) Cl.** **13-03**

(52) **U.S. Cl.** **D13/171**

(58) **Field of Classification Search** **D13/158, D13/160-177, 184; 200/11 R, 16 B; 204/297; 205/118; D23/250-252; D8/310-312; D14/217**
See application file for complete search history.

(57) **CLAIM**

The ornamental design for a remote control electrical switch, as shown and described.

DESCRIPTION

FIG. 1 is a perspective view of the front, top, and side of a remote control electrical switch showing my new design;

FIG. 2 is a front view thereof;

FIG. 3 is a top view thereof; and,

FIG. 4 is a bottom view thereof.

The broken line showing in FIG. 1 is included for illustrative purposes only and forms no part of the claimed design.

1 Claim, 1 Drawing Sheet
